US00D710681S

(12) **United States Design Patent**
Ohira et al.

(10) **Patent No.:** **US D710,681 S**
(45) **Date of Patent:** **** Aug. 12, 2014**

(54) **FIXATIVE FOR BOLT**

(75) Inventors: **Yasushi Ohira**, Sumida-ku (JP);
Akihiko Hirata, Saitama (JP)

(73) Assignees: **KFC Ltd.**, Osaka (JP); **Nichiyu Giken Kogyo Co., Ltd.**, Saitama (JP)

(**) Term: **14 Years**

(21) Appl. No.: **29/423,499**

(22) Filed: **Jun. 1, 2012**

(30) **Foreign Application Priority Data**

Mar. 16, 2012 (JP) 2012-006041

(51) **LOC (10) Cl.** **08-08**

(52) **U.S. Cl.**

USPC **D8/382**

(58) **Field of Classification Search**
